UNITED STATES PATENT OFFICE.

FRANCIS M. ROSENFIELD, OF NEW YORK, N. Y., ASSIGNOR TO IMPORT SALES COMPANY, A CORPORATION OF NEW YORK.

ELECTRIC SOCKET.

1,157,181.

Specification of Letters Patent. Patented Oct. 19, 1915.

Application filed March 1, 1915. Serial No. 11,166.

To all whom it may concern:

Be it known that I, FRANCIS M. ROSENFIELD, a citizen of the United States, and a resident of the city, county, and State of New York, have invented certain new and useful Improvements in Electric Sockets, of which the following is a description.

In many classes of electrical work, it is extremely desirable to provide a lamp socket 16 of the cheapest possible construction, but which nevertheless shall be strong, durable and which will resist the turning effort applied in screwing in a lamp. It is also often desirable to cover the screw socket with a covering which may be of insulating material and ornamental in character and within which the socket is securely held. Such condition arises in connection with the sockets used for ornamental illumination by small 20 lamps, such as that ordinarily used on Christmas trees and the like, where it is desired to color or otherwise ornament the shells surrounding the sockets and where cheapness of construction is a matter of importance.

Some of the objects of my invention are to provide a socket of this kind, which shall be simple, durable, cheap, inexpensive to manufacture, and which may be surrounded by 30 a shell of insulating or other material which may be decorated as desired and within which the socket is securely fastened to prevent longitudinal and rotary motion thereof with respect to the shell.

Referring to the drawing annexed hereto, I have shown at Figure 1 a vertical sectional view of my improved socket; at Fig. 2 a plan view thereof and at Fig. 3 a sectional view taken upon the line 3-3 of Fig. 1.

In Fig. 1, 10 indicates the socket, preferably made of relatively light brass and spun to form threads to receive the base of the lamp. The bottom of the socket is formed of a piece of insulating material 11 through 45 which passes a conducting rivet 12 to which a wire 13 is connected. The other wire 14 is connected to the side of the socket 10. Integrally formed with the upper edge of the socket 10 are a plurality of projections 15. These may be conveniently formed, either by slitting the socket longitudinally and bending out the projections or by stamping out the projections without slitting the socket. Projections 15 should be of sufficient width and strength, so that they may

resist the turning effort produced by the screwing in of the lamp in conjunction with the shell, as will be hereinafter described.

At 16 I have shown a shell which may be made of fiber, porcelain composition, or any other suitable insulating material. Upon the inner surface of shell 16 are formed a plurality of notches or depressions 17 preferably equal in number to the projections 15 formed upon the socket. The shell 16 is provided with suitable holes to permit the passage of the wires connected to the socket.

In assembling my improved device, the screw threaded socket is first inserted in the shell, the wires passing through the holes 70 provided therefor and the projections 15 are then pushed outwardly, so as to engage the depressions 17 upon the inside surface of the shell. By reason of the form of the notches and the projections, the socket is effectually 75 prevented from being pulled out of the shell or from being rotated therein. It will thus be seen that I have provided a very inexpensive construction and one which is extremely simple and durable.

While I have only shown one form of my invention, I do not desire to be limited to the form herein shown and described, since it is obvious that many changes may be made, without departing from the spirit of my invention.

What I claim is:

1. In a device of the character described, a shell of insulating material provided on its interior surface with a plurality of recesses 90 and a socket located in said chamber and provided upon its external surface with projections adapted to be forced into said recesses whereby the said projections constitute the sole means for preventing movement 95 of said socket with respect to said shell.

2. In a device of the character described, a cylindrical shell of insulating material provided on its interior surface with a plurality of recesses and a cylindrical socket of 100 sheet metal located in said shell and provided at its upper edge with projections integral therewith and adapted to be forced into said recesses whereby the said projections constitute the sole means for preventing 105 rotary and longitudinal movement of said socket with respect to said shell.

3. In a device of the character described, a cylindrical shell of insulating material provided on its interior surface with a plu- 110

rality of wedge-shaped recesses, and a cylindrical socket of sheet metal located in said shell and having its upper edge cut to form projections integral therewith and adapted to be forced into said recesses whereby the said projections constitute the sole means for preventing rotary and longitudinal movement of said socket with respect to said shell.

In testimony whereof I have signed this specification in the presence of two subscribing witnesses.

FRANCIS M. ROSENFELD.
